UNITED STATES PATENT OFFICE.

EUGENE H. LEWIS, OF ST. JOSEPH, MICHIGAN, ASSIGNOR TO THE MICHIGAN SAND BRICK COMPANY, OF SAME PLACE, AND CHICAGO, ILLINOIS.

DESIGN FOR A BUILDING-BLOCK.

SPECIFICATION forming part of Design No. 21,522, dated May 10, 1892.

Application filed December 26, 1890. Serial No. 375,899. Term of patent 14 years.

To all whom it may concern:

Be it known that I, EUGENE H. LEWIS, a citizen of the United States, residing at St. Joseph, in the county of Berrien, State of Michigan, have invented and produced a new and original Design for Building Blocks or Bricks, of which the following is a specification.

The leading feature of my design consists of an oblong marginal border surrounding the edges of the quadrangular brick and a series of irregular projections or bulged portions which have inclined sides that terminate within the marginal border, which inclined sides meet at or about the middle of the brick and form a ridge or prow that extends irregularly throughout the length of the brick, or substantially so, and such irregular projections being separated by intervening grooves or depressions.

Reference is to be had to the accompanying drawings, forming a part of this specification, in which—

Figure 1 is an elevation of a building block or brick, showing my design. Fig. 2 is a perspective view of the same, and Fig. 3 is a sectional view on the line $x-x$ of Fig. 1.

A is the oblong marginal border, which extends continuously around the edges of the brick or building-block, and B C D designate a series of irregular arbitrary projections or bulged portions, which extend beyond the plane or face of the block or brick and which are confined or contained within said border A. These projections B C D each have the two sides $e-e$ thereof inclined at an angle to

each other, the lower extremities of the inclined sides terminating within the border and flush with the same or with the face of the brick or block. The inclined sides $e-e$ of the projections C meet at about the middle of the brick, and the corresponding sides of the projections D meet nearly at the same line and are substantially continuously with the apex formed by the sides of the projections C, while the sides of the projections B meet irregularly; but they are so made as to cause the apex to join the apices of the projections C D, thus forming a ridge or prow E of irregular contour which extends continuously throughout the length of the brick or block, or substantially so, within the marginal border. The irregular projections are separated from each other by intervening grooves or depressions f.

What I claim is—

The design for a quadrangular brick or building-block, herein shown and described, the same comprising the oblong marginal border A, the series of irregular projections B C D, having their inclined sides terminating within said border, said inclined sides being joined at varying distances from said border and forming the irregular ridge or prow E, which extends longitudinally of the brick or block, as set forth.

In testimony whereof I affix my signature in presence of two witnesses.

EUGENE H. LEWIS.
